FORCE FEED LUBRICATOR

Clyde C. Farmer, Pittsburgh, Pa., assignor to The Westinghouse Air Brake Company, Wilmerding, Pa., a corporation of Pennsylvania

Application June 10, 1933, Serial No. 675,211

13 Claims. (Cl. 184—27)

This invention relates to lubricators and more particularly to a lubricator of the force feed type.

In a fluid pressure brake system, an air compressor is employed on the locomotive for supplying fluid under pressure for controlling the brakes on a train. The air compressor in common use is of the cross-compound type, having two air compressing pistons, two steam pistons for operating the air pistons, reversing valve mechanism for controlling the supply of steam to the two steam pistons, and a governor is employed to control the supply of steam to the reversing valve mechanism according to the pressure in the usual main reservoir.

13. Heretofore, it has been customary to provide lubricant for the steam actuated parts of the air compressor from the automatic lubricating system employed on the locomotive for supplying lubricant to certain moving parts of the locomotive, but it has been found, that with this system of lubricating the steam actuated parts of the compressor, the lubrication is excessive under certain conditions, while under other conditions the lubrication is inadequate.

25. Along with the above described type of lubricating system for the steam actuated parts of the compressor, it has been customary to provide lubricators, independent of the locomotive lubricating system, for supplying oil to the air cylinders of the compressor, this being necessary since a different type of oil is required for lubricating the air cylinders than for lubricating the steam actuated parts of the compressor. It has not heretofore been customary to provide lubricant 30 directly to the actuating piston in the usual steam governor, but this is desirable in order to prevent unnecessarily rapid wear of the parts of the governor.

35. One object of my invention is to provide an improved force feed lubricator particularly adapted to steam driven air compressors and operative, at all times, to provide lubricant of the proper type and in the proper amount to the different operating parts of the compressor and to the compressor governor.

40. Another object of my invention is to provide an improved force feed lubricator having a plurality of separate oil supply chambers for carrying different types or grades of lubricant adjustable pump means in each of said chambers for periodically pumping oil therefrom to the point of use in predetermined quantities, and a single member for operating the plurality of pump means.

45. Another object of my invention is to provide

a force feed lubricator which is simple in construction and easy to maintain.

Other objects and advantages will be apparent from the following more detailed description of the invention.

5. In the accompanying drawings, Fig. 1 is a vertical sectional view of my improved lubricator; Fig. 2 is a sectional view of the lubricator taken on line 2—2 in Fig. 1; Fig. 3 is a sectional view of the lubricator taken on the line 3—3 in Fig. 1; Fig. 4 is a sectional view of a portion of the lubricator, similar to Fig. 1, but showing a portion of the interior operating mechanism in full; Fig. 5 is a sectional view of the lubricator taken on the line 5—5 in Fig. 2; Fig. 6 is a sectional view taken on the line 6—6 of Fig. 2; Fig. 7 is an enlarged view of a check valve seat construction employed in the lubricator; and Fig. 8 is an enlarged sectional view of a check valve device associated with the lubricator discharge pipes, as shown in Fig. 1.

20. As shown in the drawings, my improved lubricator comprises a casing 1 having therein a dividing wall 2 forming at one side an oil supply chamber or reservoir 3 for containing a lubricant of a certain type or grade, and forming at the opposite side another oil supply chamber or reservoir 4 for containing a lubricant of a different type or grade, said dividing wall having at the center an enlarged or thickened post-like portion 5.

25. Three oil pumps 6 of identical construction, are disposed in chamber 3, and three like oil pumps are disposed in chamber 4, all of said pumps being preferably equally spaced apart.

30. The casing is provided at the bottom of chambers 3 and 4, with apertured raised portions 7 corresponding in number and disposition with the oil pumps 6. The lower end of each of the oil pumps 6 is mounted on one of the raised portions 7, a sealing gasket 8 being interposed between each pump and the respective raised portion.

35. Each of the pumps 6 is secured to the respective raised portion 7 at the bottom of the casing by means of a nut 9 having an extended threaded portion 10, which from the outside of the casing 15 is inserted through the raised portion 7 and screw-threaded into the bottom of the respective pump. For holding the pumps 6 in position while applying the nut 9, a dowel 11 is provided in the lubricator casing adjacent each pump and projects into a suitable bore provided in an ear-like extension 12 projecting from one side of the pump body.

40. The post-like portion 5 at the center of the dividing wall 2 is provided adjacent the upper end 55

with an outwardly projecting flange 13, and carried in said flange are a plurality of upwardly projecting dowels 14 corresponding in number and disposition to pump 6. Each of the pumps 6 is 5 provided with an ear 15 having a bore to receive the respective dowel 14, which construction is adapted to solidly hold the upper end of the pump 6 positioned against thrust forces which may be imposed upon the pump by the pump operating 10 mechanism, which will be hereinafter described.

Each of the pumps 6 comprises a body having in the lower end a bore in which a pump piston 16 is slidably mounted, said piston being provided with a plurality of spaced annular grooves for 15 reducing leakage past said piston. The piston 16 is carried at one end of a rod 17, which extends through a cavity 18 in one side of the pump body and an axial bore provided in the top of the pump body.

20 A spring seat 19 is mounted on the rod 17, and interposed between said seat and the upper end wall of cavity 18 is a spring 20 for effecting discharge operation of the pump 6, as will be hereinafter described. The spring seat 19 is secured 25 against relative movement to rod 17 by spring 20, by means of a ring segment 21 carried in a suitable groove in the rod and locked therein by an overhanging portion 22 of the spring seat 19.

The rod 17 extends through the upper end of 30 the pump body, and an adjusting nut 23 and an adjusting nut lock nut 24 are provided on the end of the rod 17 outside of the pump body. A wear or striking plate 25 is fitted over the rod 17 between the top end of the pump body and the 35 underside of the adjusting nut 23. It will be evident, that by changing the position of adjusting nut 23 on the rod 17, the movement of said rod and consequently the stroke of the pump piston 16 by the expansive action of spring 20, may be adjusted. The wear plate 25 is provided to receive 40 blows effected by engagement of the adjusting nut 23 upon the expansive action of spring 20, the pump body 6 being unsatisfactory for this purpose, since it is preferably made of material not particularly resistant to being upset.

45 A notch 26 is formed in the piston rod 17 near its upper end, the upper end wall 27 of said notch being sloped for engagement with cam operating means which will be hereinafter described. To 50 permit engagement of said cam operating means in notch 26, the pump body is cut away as shown at 28, and in order to maintain the rod 17 positioned for engagement with said cam operating means, a dowel 29 is mounted in the rod 17 and 55 slidably projects into a suitable groove 30 in the pump body.

The bore in which the pump piston 16 is slidably mounted, opens at its lower end into a chamber 31, into which the extended portion 10 of the 60 pump retaining nut 9 extends. The nut 9 is provided with a chamber 32 open to chamber 31, and a ball check valve 33 is contained in chamber 32 and is adapted to close communication from 65 chambers 32 and 31 to the bore containing the piston 16. A spring 34 is interposed between check valve 33 and the bottom wall of chamber 32 for urging check valve 33 to its seat. The chamber 32 is open through a passage 35 to an oil discharge pipe 36 leading to wherever it is desired to supply lubricant.

70 A circular tapered boss 37, projecting from the pump body near the lower end thereof, is provided with a chamber 38 open at its lower end to the oil supply chamber of the lubricator. A 75 passage 39 connects to the top of chamber 38

and leads to the bore containing the pump piston, said passage sloping upwardly from chamber 38 to said bore and opening into said bore at such a point as to be lapped by the piston 16 upon the initial movement of said piston in a downwardly 5 direction, that is, in the pumping stroke.

A plug 40, having screw-threaded engagement with the boss 37 within chamber 38, closes the open end of said chamber. The plug 40 is provided axially with a through passage 41 opening 10 into a chamber 42 formed within the plug, said chamber being freely open to chamber 38. A ball check valve 43 contained in chamber 42, is adapted, due to gravity, to normally close communication from chamber 38 to passage 41 leading to the 15 oil supply reservoir or chamber.

It will be noted, as shown in Fig. 7, that the screw-threaded portion of plug 40 is entirely below the plane of the seat engaged by the ball valve 43, so as to avoid, as far as possible, any tendency 20 to distort the seat when the plug is screwed home.

A strainer 44, adapted to fit over the boss 37, is applied to said boss to prevent foreign matter from passing from the oil supply chamber to the pump 6, the taper of said boss and strainer being 25 such that friction between said boss and strainer will securely retain said strainer in place.

A bearing member 45 is removably secured to the upper end of the post-like portion 5 of the dividing wall 2, preferably by screw-threaded engagement. The diameter of the bearing member 45 is less than that of the post 5, so as to provide a bearing shoulder 46. A member 47 is rotatably mounted on member 45 against the shoulder 46 and is provided with a radially projecting sector 48. Around the periphery of the sector 48 is provided a cam 49 adapted, upon rotation of the member 47, to pass through the notch 26 provided in the piston rods 17. The upper surface of the cam gradually slopes upwardly in a direction 40 opposite to the direction of rotation of member 47 and is disposed in operative alignment with the end wall 27 of the notch 26 in the pump piston rods 17, the slope of said end wall being the same as that of the cam, to provide a considerable 45 bearing surface for engagement with the cam surface. It will be evident, that as the cam 49 is rotated in the direction indicated by the arrow in Figs. 2, 3 and 4, said cam will gradually raise the piston rod 17, and therefore, piston 16 in an 50 upward direction and since the lower end of spring 20 moves with said piston rod, said spring will be compressed. As most clearly shown in Fig. 3, the cam 49 ends abruptly with the trailing edge 55 of the sector 48, so that when the cam turns 55 out of engagement with surface 27 in the piston rod 17, the compressive force of spring 20 will almost instantaneously return the piston rod 17 and piston 16 to their normal position, which is defined by engagement of the adjusting nut 23 60 with the striking plate 25.

The cam carrying member 47 is provided at its upper end with a plurality of radiating ears 51, and an inverted cup-shaped ratchet wheel 52 is secured to said ears by screws 53, dowels 54 being 65 provided in two of said ears and extending through suitable bores in said wheel for centering said wheel before applying the screws 53.

The ratchet wheel 52 is preferably made of sheet material pressed to the desired shape, with a flange 87 having ratchet teeth 55 formed therein. To form the ratchet teeth 55, a plurality of spaced slits are cut in the flange 87, corresponding with the number of teeth desired, the material between the slits being twisted to the desired 75

angle to form said teeth, it being noted that a reinforcing band 56 is retained at the base of flange 57 for connecting the ends of the teeth together, thereby reenforcing the teeth.

5 A ratchet wheel operating piston 57 is contained in an off-set portion of the lubricator casing, said piston having a stem 58 slidably extending into a suitable bore 59 also provided in said casing, the fit of said stem in said bore being 10 such as to provide a dash pot to cushion movement of the piston 57. An operating pawl 60 is pivotally carried by the stem 58 on a pin 61, one end of said pawl being bent so as to engage the teeth 55 on the ratchet wheel 52. A spring 62 15 carried in a suitable bore in piston stem 58 acts upon the pawl 60 to maintain the bent arm of said pawl in operating engagement with the ratchet teeth.

For maintaining the piston stem 58 and thereby 20 the operating pawl 60 in working alignment with the teeth 55 of the ratchet wheel, a pin 63 carried in the casing projects into the slot 64 provided in the piston stem. A spring 65 surrounding the piston stem 58 is interposed between the casing 25 surrounding bore 59 and a collar 66 provided on said stem for urging the actuating piston 57 to the position shown in the drawings. The piston 57 is subject on one face to atmospheric pressure in the oil supply chamber 4, as will be evident, 30 while the other face of said piston is subject to pressure in a control chamber 67, which is connected to a pipe 68.

35 A locking pawl 70 is contained in a chamber in another offset portion of the lubricating casing, said pawl being pivotally mounted on a pin 71. The end of pawl 70 is bent to engage the teeth 55 of the ratchet wheel 52 and a spring 72 is interposed between said pawl and the casing for holding the end of said pawl in engagement with 40 said teeth.

45 The open top of the lubricator casing 1 is closed by a cover 73 which is provided centrally with an aperture fitting over the screw-threaded end of the bearing member 45. A gasket 74 is interposed between the top edge of the casing and cover 73 and said cover is compressed against said gasket by means of a nut 75 applied to the screw-threaded end of the bearing member 45 to prevent oil leakage from the chambers 3 and 4.

50 The lubricator casing is provided with a filling spout 76, as shown in Fig. 5, the dividing wall 2, which separates oil supply chamber 3 from oil chamber 4, extending into said spout to provide a channel 77 leading to oil supply chamber 3, and 55 another and separate channel 78 leading to the oil supply chamber 4, as shown in Fig. 3. By means of the two separated channels in the one spout, the oil chambers 3 and 4 may be filled with different types or grades of lubricant without 60 danger of mixing.

65 The mouth of the filling spout 78 is closed by a cover 79 carrying a gasket 80 for effecting a seal around said mouth. The cover 79 is pivotally carried by a pin 81 secured in a lifter 82. The 70 lifter 82 is pivotally mounted on a shaft 83 secured in lugs 84 projecting from the casing. A torsion spring 85 is coiled on the shaft 83, one end of said spring being anchored while the other end acts on the lifter 82 to maintain the cover 79 in the position closing the mouth of the spout 76.

75 The lubricator casing is provided with a plurality of mounting lugs 86, by means of which the lubricator may be mounted on any desired support.

A check valve device 134 is associated with

each of the lubricator discharge pipes 36 and is preferably located in said pipes near the discharge end. Each of the check valve devices 134 is provided with an open ended chamber 135 which contains a ball check valve 136 adapted to close communication from said chamber to pipe 36 and thereby to the connected lubricator pump 6. The open end of chamber 135 is closed by an apertured plug 137, and a spring 138 is interposed between said plug and the check valve 136. It 10 will be noted that the check valve 136 is arranged in the discharge connection of the respective lubricator pump in series with the pump discharge valve 33 for reasons which will be hereinafter described. 15

In operation, fluid under pressure is alternately supplied to and vented from the piston chamber 67, by way of pipe 68, in a series of successive cycles and in any desired manner. When fluid under pressure is supplied to piston chamber 67, 20 as just described, the piston 57 is moved inwardly against the opposing pressure of spring 65, the movement of the piston stem 58 into chamber 59 acting to compress the air in said chamber so as to prevent too rapid movement of piston 57 25 which might cause breakage of parts. When the pressure in the lubricator piston chamber 67 is reduced, the force of spring 65 returns the piston 57 to its normal position.

As the lubricator piston 57 is moved inwardly, 30 the pawl 60 turns the ratchet wheel 52 in a direction indicated by the arrow in Figs. 2, 3 and 4, while the reverse movement of said piston to its normal position is relative to the ratchet wheel 52 since said wheel is locked against reverse movement by the locking pawl 70. It will be evident that for every cycle of operation of the piston 57, the lubricator ratchet wheel will be turned a predetermined degree.

As the ratchet wheel 52 is turned as just described, the cam 49, on sector 48 engaging the surface 27 on the pump piston rod 17, lifts the piston 16 upwardly on its suction stroke, which permits the chamber thus created below said piston to be filled with oil from the oil supply 45 chamber, said oil flowing past the check valve 43 to chamber 38 and thence through passage 39.

When the trailing edge 50 of sector 48 and the corresponding edge of the cam 49 move out of engagement with surface 27 on the pump piston 50 rod 17, the spring 20, which was compressed on the suction stroke of piston 16, acts to quickly move the piston 16 on its pumping stroke which acts to force the oil from the chamber below said piston past the check valve 33 into the lubricator pipe 36 and from thence, with pipe 36 filled with oil, past the check valve 136 to wherever lubricant is desired.

It will be evident from Figs. 3 and 4, that two or more of the six pumps provided in the oil supply chambers 3 and 4 may be operating on the suction stroke at the same time, but all of the pumps operate successively one after the other to pump or force a predetermined amount of lubricant into the respective pipe 36 and from 65 thence past the check valve 136.

By means of the adjusting nut 23 near the top of each of the piston rods 17, the stroke of each piston 16 and consequently the amount of oil pumped thereby may be individually regulated. This is desirable in that the amount of lubricant necessary for adequate lubrication of one part of a machine may be inadequate for another part.

The check valve 136 in the device 134 is pro- 75

vided to maintain pipe 36 filled with oil and thereby maintain the discharge check valve 33 in the oil pump sealed with oil to effectively prevent air, steam or the like from flowing past check valve 33 to the chamber below the pump piston 16 when said piston is operated on its suction stroke. The suction stroke of piston 16 is slow so that any such leakage past the check valve 33 would be liable to cause the pump to fail.

10 By removing the lubricator cover 73 and ratchet wheel 52 and pump securing nut 9, the pumps 6 may be individually removed for repair or replacement, or if less than six pumps are required in the lubricator, the opening in the 15 lubricator which receives the nut 9 may be closed with a solid plug (not shown) and the remaining pumps will then operate as intended since the operation of each individual pump is independent of that of the others.

20 The thickened or post-like portion 5 of the dividing wall 2 is provided with a bore 140 open through passage 141 at its lower end to oil supply chamber 3 and open at its upper end to an axial bore 142 provided in the bearing member 25 45, the bore 142 being open through a passage to an annular groove 143 provided around the exterior of bearing member 45. An oil wick 144, preferably of the well known type consisting of two fine wires twisted together and carrying cotton fibres between the wires, extends 30 from the bottom of bore 140 through bore 142 into groove 143 and therein is wrapped around the bearing member 45. By means of capillary action, oil is carried up the wick 144 to groove 35 143 and from thence flows onto and lubricates the bearing surfaces between bearing member 45 and the rotatable member 47. Another oil wick 145 extends through bores 140 and 142 and from thence through another passage in the bearing member 45, which passage leads to an annular 40 groove formed in the exterior surface of said bearing member above the ratchet wheel 52, and in said annular groove the wick 145 is wound around the bearing member 45. By means of the wick 145 oil is drawn to the top of the ratchet 45 wheel 52, over which it is adapted to creep to the ratchet wheel teeth 55 thereby providing lubricant between said teeth and the engaging ends of the pawls 60 and 70.

50 It will be noted that my improved lubricator is simple in construction, and the parts are readily accessible for removal or replacement, each of the oil pumps is individually adjustable to regulate the amount of oil pumped and is individually removable, all of the operating parts 55 are contained within the lubricator casing and means are provided for lubricating these parts. Only two oil chambers and six pumps are employed to illustrate the invention, but it will be evident that the lubricator casing may be divided to provide more individual oil chambers if desired and the number of pumps employed 60 may be varied to meet different circumstances.

65 While one illustrative embodiment of the invention has been described in detail, it is not my intention to limit its scope to that embodiment or otherwise than by the terms of the appended claims.

Having now described my invention, what I 70 claim as new and desire to secure by Letters Patent, is:

75 1. A lubricator comprising a casing having an oil supply chamber, a lubricant pump mounted in said chamber with one end removably secured to the bottom wall of said casing, a member extending upwardly from said bottom wall,

and means associated with said member and said pump near the other end of said pump and adapted to engage in the act of positioning said pump in said casing, to hold the pump rigidly in position.

2. A lubricator comprising a casing having an oil supply chamber, a lubricant pump mounted in said chamber with one end removably secured to the bottom wall of said casing, a member extending upwardly from said bottom wall, 10 and a dowel associated with said member adapted to engage in a bore in said pump near the other end of said pump in the act of positioning said pump in said casing, to hold said pump rigidly in position.

3. A lubricator comprising a casing having an oil supply chamber, a lubricant pump mounted in said chamber and comprising a body member having aligned bores and a recess intermediate said bores, a piston working in one bore, 20 a piston rod working in the other bore and extending through said recess and operatively connected to said piston, a spring mounted in said recess and acting on said rod to urge said rod to move said piston in one direction, a rotatable 25 cam adapted to engage said rod for moving said rod and piston in the opposite direction, and coacting means in said body member and rod for maintaining said piston rod in operative alignment with said cam.

30 4. A lubricator comprising a casing having an oil supply chamber, a lubricator pump mounted in said chamber and comprising a body member having aligned bores, a piston working in one bore, a piston rod working in the other bore and 35 operatively connected to said piston, spring means for urging said piston rod and piston in one direction, a rotatable cam for urging said piston rod and piston in the opposite direction, said piston rod having a notch providing a shoulder adapted 40 to be engaged by said cam, said body member having an opening through which said cam extends to engage said shoulder, and means associated with said body member and piston rod for maintaining said piston rod in operative relation to 45 said cam.

5. A lubricator comprising a casing having an oil supply chamber, a member extending upwardly from the bottom wall of said chamber, a plurality of individual oil pumps arranged concentrically 50 around said member, rotatable means associated with said member for operating said pumps on their suction stroke, pressure exerting means for operating said pumps on their pumping stroke, an inverted cup-shaped ratchet wheel secured to 55 said rotatable means and extending downwardly over the top of said pumps, and pressure actuated means for rotating said ratchet wheel.

6. A lubricator comprising a casing having an oil supply chamber, a member extending upwardly 60 from the bottom wall of said chamber, a plurality of individual oil pumps arranged concentrically around said member, bearing means secured to said member, cam means rotatably carried by said bearing means for controlling the operation 65 of said pumps, a ratchet wheel secured to said cam means, said member having a passage opening into said oil supply chamber and leading to a passage in said bearing means, the last mentioned passage leading to the bearing between said cam 70 means and bearing means and also to the top surface of said ratchet wheel, and wick means extending from the bottom of the oil supply chamber to said bearing and to the top of said ratchet wheel.

7. A lubricator comprising a hollow casing having a partition wall dividing the interior of said casing into two separate oil chambers for holding different types or grades of oil, an oil pump in one of said chambers for pumping oil only from said chamber to a point of lubrication, an oil pump in the other chamber for pumping oil only from the last mentioned chamber to a different point of lubrication, cam means carried by said partition wall for controlling the successive operation of both of said pumps, a cover enclosing said chambers, pumps, and cam means, a filling spout projecting from one side of said casing, said partition wall extending into said spout and providing one channel leading to one of the oil supply chambers and another and separate channel leading to the other oil supply chamber, and a cover for closing the mouth of said filling spout.
8. A lubricator comprising a casing having an oil supply chamber, a post-like member carried by the bottom wall of said chamber and extending upwardly therein, a plurality of individual oil pumps arranged concentrically around said post-like member and removably secured to the bottom wall of said chamber, coacting means associated with said bottom wall and each of said pumps for positioning said pumps in said chamber, means remote from said bottom wall securing said pumps to said post-like member, and rotatable means carried by said post-like member and controlling the operation of said pumps.
9. A lubricator comprising a casing having an oil supply chamber, a post-like member carried by the bottom wall of said chamber and extending upwardly therein, a plurality of individual oil pumps arranged concentrically around said post-like member and removably secured to the bottom wall of said chamber, coacting means associated with said bottom wall and each of said pumps for positioning said pumps in said chamber, means remote from said bottom wall securing said pumps to said post-like member, a bearing member secured in the outer end of said post-like member, a cam member rotatably mounted on said bearing member and operative upon rotation to control the operation of said oil pumps, and means for operating said cam member.
10. A lubricator comprising a casing having an oil supply chamber, a post-like member carried by the bottom wall of said chamber and extending upwardly therein, a plurality of individual oil pumps arranged concentrically around said post-
- like member and removably secured to the bottom wall of said chamber, coacting means associated with said bottom wall and each of said pumps for positioning said pumps in said chamber, means remote from said bottom wall securing said pumps to said post-like member, rotatable means carried by said post-like member for controlling the operation of said pumps, the upper side of said chamber being open, and a removable cover secured to said bearing member and closing the upper side of said chamber.
11. A lubricator comprising a casing having an oil supply chamber, an oil pump secured to said casing within said chamber, rotatable cam means carried by said casing for controlling the operation of said pump, a gear wheel carried by said cam means, and means for rotating said gear wheel comprising a piston reciprocatively mounted in a bore in said casing, a pawl associated with said piston and engaging said gear wheel and operative by said piston to turn said gear wheel, and means for maintaining said pawl in operative alignment with said gear.
12. A lubricator comprising a casing having an oil supply chamber, an oil pump secured to said casing within said chamber, rotatable cam means carried by said casing for controlling the operation of said pump, a gear wheel carried by said cam means, means for rotating said gear wheel comprising a piston reciprocatively mounted in a bore in said casing, a stem carried by said piston and slidably extending into a bore in said casing, a pawl adapted to engage one side of said piston and movable by direct contact therewith for turning said gear wheel, and means associated with said stem and carrying said pawl.
13. A lubricator comprising a casing having an oil supply chamber, an oil pump secured to said casing within said chamber, rotatable cam means carried by said casing for controlling the operation of said pump, a gear wheel carried by said cam means, means for rotating said gear wheel comprising a piston reciprocatively mounted in a bore in said casing, a stem carried by said piston and slidably extending into a bore in said casing, a pawl carried by said stem and operated by said piston for turning said gear wheel, said stem having a longitudinal slot, and a pin carried by the casing and loosely extending into said slot for maintaining said pawl in operative alignment with said gear.

CLYDE C. FARMER.
